INDICATOR HOUSING FOR AN ELECTRICAL CIRCUIT TESTER

Marvin J. Freed, Tel Aviv, Israel, assignor to Eldar Electronics, Kibbutz Yad Mordechai, Israel

Filed Oct. 16, 1973, Ser. No. 407,001

Term of patent 14 years

Int. Cl. D10—07

U.S. Cl. D10—46

FIG. 1

FIG. 2

FIG. 3

FIG. 1 is a top, right, and rear perspective view of an indicator housing for electrical circuit tester showing my new design;

FIG. 2 is a front elevational view thereof;

FIG. 3 is a right side elevational view thereof, the left side being a mirror image thereof.

I claim:

The ornamental design for an indicator housing for an electrical circuit tester, as shown.
